UNITED STATES PATENT OFFICE.

HUGO SCHREFFER, OF WEST HOBOKEN, NEW JERSEY.

NOVELTY.

1,376,167.

Specification of Letters Patent. Patented Apr. 26, 1921.

Application filed November 19, 1919. Serial No. 339,091.

To all whom it may concern:

Be it known that I, HUGO SCHREFFER, a citizen of the United States, and resident of West Hoboken, in the county of Hudson and 5 State of New Jersey, have invented certain new and useful Improvements in Novelties, of which the following is a specification.

This invention relates to novelties, and has for its main object the provision of an 10 attractive novelty which is simple in operation, inexpensive in cost of manufacture, and which will provide a plaything for both young and old.

Another object of the invention is the 15 provision of a novelty having a mechanical operation, the mechanism thereof being concealed from view and creating an air of mystery to a spectator.

The above and other objects will become 20 apparent in the description below, in which characters of reference refer to like named parts in the accompanying drawings, which form a part of this application.

Referring briefly to the drawings, Figure 25 1 is a front view of my device.

Fig. 2 is an abbreviated front view of the device showing the figure therein in a different position than that shown in Fig. 1.

Fig. 3 is another abbreviated front view 30 showing the manner of operation of the device.

Fig. 4 is a cross-sectional view of the same substantially on the line 4-4 of Fig. 1.

Fig. 5 is a view of the strip of paper 35 carrying the illustrations shown in Figs. 1 and 2.

Referring briefly to the drawings, the 40 numeral 1 represents a frame having an opening 2 therein. A strip of paper of a width slightly greater than that of the said opening, and of a length several times larger than the same, indicated by 7, is secured to the rear of said frame by its upper and 45 lower ends 7a; glue or any convenient paste may be used for this purpose. Said strip is provided with two pictures or sketches, one of which represents a figure in one position, and the other in another position; 50 for the purpose of illustration I have chosen to present the figure of a person's head showing the person awake in one position

and asleep in the other, although I do not of course, desire to limit myself to these subjects. A space 11 is provided on said strip between said pictures 3 and 4. A flat piece of material 10, such as pasteboard, for instance, is secured against the blank space 11, as by glue, and a handle 5 is secured to the rear of said space, in the 55 manner shown, for the purpose of operating the device. A flat member 8, of the same material, has a slot 12 therein, through which the said strip 7 passes twice, as shown; said member 8 is vertically slidable. A narrow member 6, also of the same material, is pasted by its ends to the sides of said slot 12 and just over the fold of the strip 7 therein so as to conceal the same, yet not prevent the strip 7 from being able 60 to freely pass to and fro through said slot. 65

It is now apparent that, assuming the picture shown in Fig. 1 to be in view, and the handle in the upper position, if said handle is moved down, the members 8, 6 and 70 10 will follow, and the strip 7, the ends of which remain stationary, will be moved in the manner which is clear from Fig. 4, so that the picture shown in Fig. 1 will disappear and the picture shown in Fig. 2 75 80 will appear, the member 6, during this transformation, passing from the upper to the lower part of the opening 2, so that it impresses the observer as though the said member 6 erases the picture which first was 85 visible, and its movement appears to create the second picture. Again, upward motion of said handle will cause disappearance of the second picture and reappearance of the first. 90

Having thus described my invention, what I claim and desire to secure by Letters Patent is as follows:

A device of the class described comprising 95 a frame having an opening therein, a strip of paper having two pictures drawn thereon, one of said pictures showing the figure of a person in one position and the other showing said figure in another position, said pictures being longitudinally 100 spaced apart and the ends of said strip being secured to the rear of said frame, a handle, an enlarged member rigid with the upper end of said handle, the central por-

tion of said strip being attached about said enlarged member, a slotted member lying between said enlarged member and said frame, said strip passing through said slot 5 in both directions, a member bridging said slot so as to conceal the line separating the two folds of the strip passing through said

slot, said handle being movable alternately up and down.

Signed at New York, in the county of 10 New York and State of New York, this 11th day of November, 1919.

HUGO SCHREPPFER.
